METHOD OF THERMOLYZING LIQUIDS

Alfred Oberle, Washington, D. C.; Grace Oberle administratrix of the estate of said Alfred Oberle, deceased.

Application April 30, 1930, Serial No. 448,704
Renewed August 14, 1935

28 Claims. (Cl. 196—58)

This invention relates to a method of thermolyzing fluids, liquid substances, oils or substances which may be liquefied by heat.

The objects of the invention are to provide a process wherein the heat required for the changes involved in the process are in part provided by transfer from a medium, heated to a very high temperature, with which the substance comes into intimate contact, in such a manner as to cause the desired changes without danger of superheating and the consequent excessive undesirable changes, the conditions of temperature and pressure being controlled throughout.

The use of heated mercury in the liquid as well as in the vapor phase for the indirect transfer of heat to liquids to be distilled or heated for other purposes is well known, in the prior art. It should be noted, however, that in the prior art processes the heat is transferred through the walls of a heat exchanger only, and is not directly transferred as in the process of this application, by the intimate mixture of the heated mercury with the other component.

Where mercury has been used for direct heat transfer to the oil to be treated, the two liquids were kept at pressures below atmospheric or else the difference in the temperature of the mercury and the tool oil used was so great that much heat carried by the mercury was expended long before the temperature of the oil reached a point high enough for the desired changes, and thus the quantity of mercury was of necessity very large. The initial heating of the oil by ordinary means, prior to the mixing is proposed in this application.

In the known cases in which the heated mercury vapor was mixed with hot oil vapors, control of the temperature and pressure of the oil and mercury vapors, during the heat exchange was not provided for. Due to the fact that in the process disclosed here, the oil and mercury are heated under pressure prior to mixing and are still under pressure when mixed in a tube which may receive additional external heat, the temperature of the mixture as well as the duration of the contact and the velocity of the flow of the mixture may be controlled.

In the process here disclosed, the oil or other fluid substance and the mercury are heated in separate coils and under pressure in a furnace, combined in a thermolyzing tube, still under pressure, though reduced, in such a manner as to insure intimate mixing and efficient heat transfer, passed into a reaction chamber or vaporizer where changes are continued and

vaporization, separation and fractionation take place, preferably still under elevated pressure, although atmospheric pressure or vacuum may be employed, and from which the volatile products, unvaporized residue and the mercury can be removed for further treatment, diverted or returned to the system as seems desirable or necessary.

The details and advantages of the process will be best understood with the aid of the diagram shown in the drawing.

The substance to be treated is forced into the system by pump 1 through line 2. It may be preheated in the coil 3 in the vapor space of chamber 4, valve 5 being open and valve 6 closed. From coil 3 in the vapor space in the chamber 4 the preheated oil passes through valve 7 (valve 8 in auxiliary feed or discharge line 8' being closed) valves 9 and 10, line 11, valve 12, pump 13, coil 14, valve 15, line 16, valves 16 and 17 and into coil 18 where it is intimately mixed with heated mercury (and may be further heated externally before it passes into the chamber 4). The mixture of oil and mercury is then passed through the pressure release valve 19, and impinges (together with the mercury) on the baffle plate 20. Vapors given off in chamber of dephlegmator 4 are fractionated in the upper portion thereof and the uncondensed vapors leave by line 21 equipped with pressure valve 21', and are cooled in coil 22 of condenser 23.

The condensate formed here may be returned to the system through valve 24 and line 25. Uncondensed vapors and, if desired, the condensate together with uncondensed vapors leave the condenser coil through pressure release valves 26 and 26' and may be withdrawn for further treatment through valve 26' or returned to chamber 4, by means of lines 45 and 47 and valves 48 and 46 by means of a pump not shown.

Mercury enters the system by line 27 through valve 28, charging pump 29, line 30, high pressure pump 31, line 32, and is heated in coil 33, passes through pressure release valve 34 into the enlarged (thermolyzing) coil 18, and mixes intimately with the oil which enters this coil at a point at or near valve 34 and at such an angle as to insure proper mixing. From coil 18, as above stated, the mixture passes through valve 19 into the tower 4 and against the baffle plate 20.

Unvaporized oil and the condensed mercury settle to the bottom of the chamber 4 in two layers. Any excess of the hot mercury layer 35 below, may be continuously withdrawn through line 36, valve 37, to be returned to the heating

system by pump 31. The residue which collects on the top of the mercury pool in the bottom of the tower 4 is withdrawn through line 38, and may be discharged into the flashing chamber 39 through pressure release valve 40, or may be withdrawn through valve 41, pipe 42. Gauge 43 indicates the mercury level in pool 35 (or chamber 4). Vapors given off from the residue in tank 39 are withdrawn through valve 44 in line 45, and may be combined with the vapors passing through valve 26 or they may be returned to the chamber 4 through valve 46, line 47, or they may be withdrawn from the system through valve 26''. The residue formed in tank 39, is solid, can be removed through manhole 49. Tank 39 is provided with a gauge glass 50. Line 51 serves to introduce steam into the bottom of chamber 4 through valve 53. The residue collected in the bottom of tank 39 may be diverted from the system through line 54, valve 55, connection 56, and valve 57 (valve 58 closed). Or it may be pumped through coil 33 by means of pump 29, with valves 55 and 58 open and valves 67 and 28 closed.

25 The condensed oil or any mercury carried over into the vapor line 21 may be returned to the chamber 4 through valve 24, line 25, valve 59 and line 60. The condensate formed in the coil 22 may be returned to the upper part of the dephlegmator through line 61, valve 62, pump 62', line 63 and anyone or more of the valves 64, 64a, 64b, 64c, or it may be returned to the heating system through line 63', valve 63'', and line 11. Provision is also made to return the condensate from coil 22 into the bottom of chamber 4, forcing it through the pool of hot liquid mercury 35 by means of pump 69 in line 61, then valves 68 and 70. In order to control the fractionation in chamber 4, provision is made for the introduction of cool or preheated charging stock into the dephlegmator through line 11, valve 72. Two auxiliary pumps 73'' and 74'' are provided in lines 73 and 73'.

45 For the introduction of cold or preheated charging stock into coil 18, line 75, valve 76, line 78 and valve 79 can serve. An extra amount of oil (simultaneously with the charge entering through line 2) may be introduced through line 8' by means of pump 1'. The pump 1' will furnish the pressure necessary to force the charging stock through valve 76, lines 75 and 78 and valve 79 to enter the thermolyzer 13 together with hot oil from coil 14, through pressure reduction valve 17. By means of valve 80' in by-pass 80, oil may be diverted from the system, or introduced by suitable connections. Hot oil may be diverted from the heating coil 14 through valve 79 or by-pass 80 and reintroduced into the heating system through line 75 and valve 76 thus reentering line 11, or it may be introduced into the dephlegmator 4 through by-pass (not shown in the diagram) connecting lines 75 and 71 (with a valve interposed).

60 Provision is also made for the introduction of the heated oil and the heated mercury through separate line 82, valve 83, and coil 18, and valve 19, respectively, into the vaporizer 4 (valve 84 being closed). By means of valve 85 in line 11, it is possible to send the entire charging stock, or part of it, together with the mercury, through coil 33. Valve 86 is in a line connecting coil 33 with lines 78 and 75.

65 The charging stock or oil from coil 14, after entering the dephlegmator 4 by line 71 and being stripped therein, together with the reflux, may

be returned to the charging line 11 by means of line 73, pump 73'' and valve 74.

70 Line 32' represents a by-pass by which mercury can be sent into heating coil 14 instead of 33, so that use of the coils is reversed. To do this, valves 30' and 12 must be closed and 30'' and 85 opened to admit the charging stock to line 32 and coil 33 through pump 31.

75 The pumps may be of any conventional type and supplied with by-passes for the reversal of the direction of the flow of oil in the lines to which they are connected, or the by-passes may serve to eliminate the pumps entirely or temporarily.

80 The drawing is only diagrammatic and the dimensions of the various parts may be altered, especially those of the heating and thermolyzing coils. Pyrometers, pressure gauges, and various devices for control and safety may be introduced as and wherever desired.

85 The underlying principles of the invention can be further explained to advantage by way of an example illustrating one practical embodiment of the process and of apparatus suitable for carrying it into effect.

90 In a typical operation, the oil to be thermolyzed is charged into the system by pump 1, through line 2, valve 5, preheating coil 3, valve 7 (with valves 6 and 8 closed) through valves 9 and 10 (valves 12 and 16 closed), line 11, valve 12, (with valve 85 closed), high pressure pump 13, heating coil 14, valve 15, (valve 83 closed), line 16, valve 84, (valves 79 and 81 closed), and pressure reducing valve 17. Here the heated oil enters the thermolyzing coil 18 at an angle, and imparts a centrifugal or turbulent motion to the mixture which it forms with the mercury which also enters the thermolyzing coil. The mercury is charged into the system on the suction side of charging pump 29 through line 27 and valve 28. It passes through line 30, valve 30' and is forced through line 32 by high pressure pump 31 and into heating coil 33 in which it is heated to its maximum desired temperature. It then passes through pressure reducing valve 34 into the thermolyzing coil 18, which is preferably of larger diameter than either heating coil 33 or 14. The thermolyzing coil 18 is located in that part of the furnace, not shown in the diagram, through which the flue gases pass just prior to their exit. The heating furnace, including the flue, may be constructed in any conventional manner, with damper arrangements in the flue which will permit a regulation of the temperature especially in that part of the furnace in which coil 18 is located. It is possible to keep the coil 18 at such a temperature that practically no heat transfer between the mixture in the coil and the flue gas takes place, or the temperature in this part of the furnace may be adjusted so that a slight heat exchange in favor of thermolyzing coil 18 may take place or vice versa. This feature of regulating the temperature at which the thermolyzing coil is kept, somewhat independently of the temperature of the mixture of the oil and mercury entering therein, is important.

95 Any desired pressure may be maintained on the oil in heating coil 14 as well as in the connecting lines 16, by means of the high pressure pump 13 and valve 17. Any desired high pressure, independent of the pressure maintained on the oil in coil 14, may be maintained on the mercury in heating coil 33. This pressure on the oil, as well as on the mercury, is reduced at, or near the point where these two liquids are discharged.

or sprayed tangentially into the common thermolyzing tube 18. By means of the pressure reduction valve 19, a pressure may be maintained in the thermolyzing coil, notwithstanding the fact that a pressure drop of .300 lb. per square inch may have taken place where the two liquids entered the thermolyzing tube. Through this pressure reduction valve 19, the oil and mercury mixture (substantially in the form of a mist) enters expansion or vaporization chamber 4.

Near the point where the mercury and oil mixture enters chamber 4, a baffle plate 20 is so arranged that it gives the mixture a rotating motion, thus aiding in the separation of the various constituents. The condensed mercury as well as the non-vaporized parts of the oil will settle to the bottom of this chamber 4 where the mercury forms pool 35 over which the non-vaporized parts of the oil will collect in fluid form to be continuously or intermittently withdrawn from the system through line 38. Gauge glass 43 serves to indicate the level of the mercury pool 35. Any loss of mercury in the system may be made up by the introduction of equivalent quantities through line 21, connected to a source of mercury supply, valve 28 and charging pump 29, which is otherwise usually idle during the run after the necessary amount of mercury has been introduced into the system.

The volatile parts which separate in the tower 4 are fractionated in the upper part of this tower which may contain any fractionating or rectifying device as bubble plates, perforated baffles or the like for intimately contacting liquids or vapors. The temperature in the upper part of the vaporizer 4 can be regulated by means of the amount of cool charging stock allowed to flow through coil 3 which in turn can be controlled by manipulation of valves 5, 6, 7 and 8. By means of line 11 and valve 72, cold or preheated charging stock may also be admitted into the upper part of chamber 4 which acts as a fractionator or diphlegmator.

Provision is made for the withdrawal of the reflux condensate from the tower at different heights through lines 73 and 73' which lines may be provided with auxiliary pumps 73'' and 74'' and valves 74 and 74'. This condensate together with any unvaporized charge introduced through line 71 may be returned to the charging stock in line 11. The uncondensed vapors leave chamber 4 through pressure reduction valve 21', line 21 and pass into a condensing coil 22 in cooler 23. In this coil, any mercury which may have been carried over will be condensed and returned by gravity through valve 24 into line 25 to chamber 4, through valve 59 and line 60.

The condensate formed in the cooling coil 22 may be returned to the upper part of chamber 4 by means of line 61, valve 62, pump 62', line 63, and valves 64, 64a, 64b, and 64c, or to the bottom of chamber 4 by means of valve 68, line 61, pump 69 and valve 70, and be forced through the heated mercury pool 35 to be reboiled, the volatile parts escaping to be refractionated while the heavier constituents will mix with the reflux and residue which has collected on the top of the mercury pool 35, to be withdrawn therefrom together with the residue and either diverted from the system through valve 41 in line 42 or else introduced into one of several flashing drums 39 (only one shown) from which the volatile parts may be removed through valve 44, line 45.

The condensate from coil 22 may also be re-

turned to the charging stock in line 11 by means of line 63' and valve 63''. These vapors from flashing chamber 39 may be returned wholly or partially to chamber 4 or combined with the vapors and condensate passing through valve 26, to be withdrawn through valve 26' for further cooling or treating, or they may be withdrawn through valve 26''. Any mercury flowing over into the flashing drum 39 and also the residue may be returned to the system by line 54, valves 10 55 and 58 (valves 57 closed).

Depending on the character of the oil and the mode of operation it may be desirable to have the level of the mercury pool 35 so high that enough hot mercury flows over into the flashing drum 39 together with the residue, to form a pool of hot mercury in the bottom of this tank also, the level of the mercury here being controlled by line 54, valve 55, and either valve 57 or 58 in line 56 by means of which it may be withdrawn from or reintroduced into the system. This hot mercury pool in the flasher will aid in vaporization of the oil, especially if steam also is injected through the mercury, and also in preventing the residue from clogging the flasher. 25 The residue from the flashing drum 39 may be withdrawn from the system together with any mercury present by means of line 54 and valves 55 and 57 or may be removed through man-hole 49. 30

Steam may be injected into flashing chamber 39 or through the mercury pool in chamber 4 or both by means of line 51, valves 52 and 53.

The pressure in chamber 4 may be maintained at any desired value, above, at, or below atmospheric. 35

Pressure reducing valve 21' is used principally for regulation of pressures above atmospheric, valve 26 for atmospheric. For pressures below atmospheric, valve 26' or 26'', or both, are used connected to a source of vacuum. 40

The chief features of the process are the following:

The charge of the hot oil is brought into intimate contact with atomized, highly heated mercury in such a manner that every molecule of oil is thermolyzed by a very brief contact with the hot mercury. The thermolyzing tube is kept at such a temperature that heat loss therefrom is either avoided or negligible, without, at the same time, permitting sufficient heat transfer through the walls of the tube to cause skin cracking, coking, or superheating of the contents of the tube on its inner surface. The mercury prevents the clogging of the tubes and the solidifying of the residue in the system. 55

The mercury is heated under pressure to a very high temperature and the oil nearly to cracking temperature also under pressure before they are atomized into the thermolyzing oil. 60 The return of the hot mercury to the system from the bottom of the chamber 4 is an economy in heat.

If the oil and mercury mixture entering the vaporizer is too hot, it may be cooled by admitting oil from line 82 through valve 83 which will be mixed with the oil and mercury mixture as it impinges upon the baffle plate 20. 65

Due to the fact that the mercury is non-inflammable and non-combustible, there is a great reduction of fire and explosion hazard. The mercury has a catalytic effect on oil. Other features are the reheating and purifying of the reflux condensate by passing it through the pool of hot mercury in the bottom of the vaporizer 4. 70 75

Further details of the apparatus and special modifications thereof are as follows:

As the chief purpose of the furnace is the heating of the mercury and the amount of the mercury is so small in comparison with that of the oil treated, the tubes can be small, and the furnace itself can be relatively small, and needs no special construction such as is necessary when cracking of oil is accomplished by the transfer 10 of heat from the furnace through the walls of cracking tubes.

The mercury is heated in the hottest part of the furnace. The coils for heating the oil nearly to cracking temperature may be placed in a cooler 15 part of the furnace.

As the thermolyzing coil needs only slight heating, if any, it can be placed in the flue nearest where the flue gases leave the furnace. Although the direction of flow of oil in the thermolyzer is 20 preferably from top to bottom, it might be desirable that the direction be reversed. To do this, slight alterations in the connections of the mercury and oil coils with the thermolyzing coil would be necessary. In addition to the control of 25 temperature in the thermolyzer by dampers in the flue, temperature of the oil and mercury from the coils, pressure alterations and so forth, further regulation of temperature can be accomplished by the introduction of cool oil into the 30 system near the pressure reduction valve by means of valves 36 or 79.

Due to the high velocity with which the intimate mixture of the two liquids is passed through the thermolyzing tube, it is possible to use mercury heated to a very high temperature before it 35 enters the thermolyzing tube thus insuring very effective, although brief, contact of the highly heated mercury particles with the oil to be treated before they are expanded in the vaporizing chamber.

40 There is flexibility in the operation due to the fact that the heat stored in the mercury is made available in parts of the system, entirely outside of the furnace. This allows for an exceptionally fine control of conditions of temperature, pressure and time for the reactions.

At the point where the oil and mercury mixture enters the vaporizing chamber, a baffle plate or other device is so arranged as to give the mixture a whirling motion downward, as well as upward, which will aid in the separation of the light oil from the heavy oil and mercury. Provision is 50 made in the upper part of the vaporizer to fractionate the vapors by means of well-known baffle plates or similar fractionating equipment. Provision is also made for the condensation, separation, and return of the mercury carried by the oil 55 into the upper part of the vaporizer.

The temperature of the vaporizer can be controlled by the introduction of cold or preheated 60 charging stock, reflux condensate, or condensate with steam, either wet or superheated, into the chamber as well as by indirect contact with the charging stock in preheating coil 3.

Hot oil from coil 14, together with charging 65 stock, can be introduced into the chamber through line 16, valves 84 and 79, line 75 and by-pass (not shown) around valves 76 and 72 (or through valves 76 and 72) into line 71, and then be returned to the heating system through line 73. auxiliary pump 73", valve 74 and line 71. The 70 injection of steam from line 51 through valve 53, mercury pool 35, and the residue above the mercury also aids in the vaporization and separation.

Also, if desired, the hot mercury and hot oil 75 may be sent from the coils into chamber 4 with-

out first combining them in the thermolyzing coil, that is, the oil can go directly from heating coil 14 through valves 15 and 23, with valve 34 closed, and the mercury pass through the thermolyzing coil and enter the chamber through valve 16. The 5 baffle plate or other appropriate device serves to aid the mixing of the vapors and to give the desired whirling motion in the chamber.

The use of mercury in this process and apparatus has many advantages, among which are: It 10 is technically possible to heat it to a very high temperature; it gives up its heat very rapidly, especially if atomized or vaporized, because of the intimate contact that it can make with the oil, without however, being soluble therein; both skin 15 cracking and superheating of the oil are avoided; the amount of mercury and the temperature to which it must be raised are readily determined and controlled; also, because of its liquid state and its high specific gravity, it can be readily fed 20 and transported with the aid of appropriate reservoirs and pumps; it separates from the oil and residue very readily, and (because of its heated condition) aids in keeping the collecting oil residue in the chamber fluid, and in vaporizing the 25 more volatile constituents.

Furthermore, its use is economical, because it can so conveniently be raised to the maximum temperature desirable in oil treatment, the amount needed is not large, its recovery is practically complete, and it can be returned to the system at a relatively high temperature; due to its specific gravity, it aids in causing turbulence and prevents clogging.

By careful manipulation of the pressures after 35 the mercury leaves the heating coil 33 at its maximum temperature and pressure, it is possible to have a pressure in the thermolyzing coil 18 such that an appreciable amount of the mercury which tends to vaporize on entering therein, (due to pressure reduction), will give up its heat of vaporization to the oil and be again chiefly liquid as it reaches the pressure release valve 19 to enter the expansion chamber 4. With the pressure decrease on entering the chamber, it will again tend to become vapor but with a lower temperature. There will then be the same phenomenon as already described in the thermolyzing coil. Appreciable heat will be transferred from the mercury to the oil at a temperature high enough to permit continued reaction and, at the same time, a high degree of vaporization of the oil. The heat remaining in the liquefied mercury which collects in the pool is partially spent in vaporization of the residue in the chamber 4 or later in the flashing chamber 39, and partially reserved in the mercury which is returned in a 50 still heated condition to coil 33 to be used over again.

It is readily apparent that the process, described above with its various suggested modifications, 60 may be applied to various kinds of crude oil, residues, hydrocarbon oils, carbonaceous material containing hydrocarbons, and other substances which are fluid at ordinary temperatures or readily liquefied by the application of heat, in cases 65 where controlled heating followed by the vaporization of some of the products is desired.

Instead of using mercury as a heat transfer media, an alloy with a very low melting point such as, for example, Rose or Wood metal may 70 be used. It is also understood that instead of mercury, a mercury amalgam which is liquid at temperatures such as employed in this process may be used.

In order to start up the process when a low 75

melting point alloy or mercury amalgam is used, it is only necessary to heat the alloy or the amalgam to a temperature sufficiently high before it is introduced into the system through line 27 and pump 53.

Once the process is in operation, this heat transferring material will always be kept at a temperature sufficiently high to prevent congealing or solidification.

10 I claim:

1. A method of converting hydrocarbons comprising intermingling the hydrocarbons with liquid mercury heated under pressure to a temperature high enough to bring the mixture of hydrocarbons and mercury to conditions sufficient to convert the hydrocarbons, passing the mixture through a thermolyzing zone in a stream of restricted cross-sectional area, introducing the mixture into a zone of reduced pressure, distilling off the hydrocarbon vapors and collecting the mercury in a pool, withdrawing volatile, liquid and solid material for further treatment.

2. A method of converting hydrocarbons comprising intermingling the hydrocarbons with liquid mercury heated under pressure to a temperature high enough to bring the mixture of hydrocarbons and mercury to conditions sufficient to convert the hydrocarbons, passing the mixture through a thermolyzing zone where primary cracking takes place, in a stream of restricted cross-sectional area introducing the mixture into a zone of reduced pressure, where secondary cracking takes place, distilling off the hydrocarbon vapors, condensing the vapors, collecting the mercury in a pool and reintroducing the condensate or pressure distillate into the zone by injecting the same into the pool of highly heated mercury, withdrawing volatile, liquids and solids for further treatment.

40 3. A method of converting hydrocarbons, comprising intermingling the hydrocarbons heated to a temperature just below the point of decomposition with a metallic liquid heated to a temperature high enough to bring the mixture of hydrocarbons and liquid metal to conditions sufficient to convert the hydrocarbons, forcing the mixture thru a thermolyzing zone in a stream of restricted cross sectional area under conditions of high velocity and turbulence to bring about conversion without appreciable carbon formation, introducing the mixture into a zone of reduced pressure, distilling off the volatile hydrocarbons, collecting the unvaporized and condensed material in a pool and withdrawing volatiles, liquids and solids for further treatment.

45 4. A method of thermolyzing hydrocarbons, comprising heating the hydrocarbons close to a temperature at which thermal decomposition of the higher boiling constituents would occur at atmospheric pressure, heating mercury to a higher temperature and forcing said heated hydrocarbons and heated mercury substantially in the liquid phase thru a thermolyzing zone, in a stream of restricted cross sectional area, applying external heat to said thermolyzing zone and expanding the mixture into an expansion chamber wherein separation of the mercury from the oil and fractionation of the oil vapors takes place, collecting the mercury in a pool and recycling the same and separately removing the condensed and unvaporized hydrocarbons and other residual material formed, from the surface of the pool of hot mercury for further treatment and withdrawing uncondensed vapors and gases.

5. A method of converting hydrocarbons, comprising heating the hydrocarbons close to the limit of molecular stability of the higher boiling point constituents, mixing said hydrocarbons with a metallic liquid, heated under superatmospheric pressure to a temperature above that of the aforementioned hydrocarbons substantially in the liquid phase, passing the mixture thru a thermolyzing coil in an elongated stream of restricted cross sectional area under conditions of velocity, turbulence and temperature to bring about conversion of the hydrocarbons without substantial carbon formation, expanding the mixture into a fractionator, withdrawing vapors and gases, collecting the unvaporized and condensed hydrocarbon and metallic material in a pool, removing the unvaporized and condensed hydrocarbons from the surface of the pool, flashing same into a separate chamber, injecting steam into said chamber and withdrawing the volatile, liquid and solid material from the system.

10 6. A method of converting hydrocarbons, comprising intermingling the hydrocarbons with a metallic liquid heated under pressure to a temperature high enough to bring the mixture of hydrocarbons and liquid metal to conditions sufficient to convert the hydrocarbons, passing the mixture in a turbulent motion thru a thermolyzing zone in a stream of restricted cross sectional area, introducing said mixture into a zone of reduced pressure, distilling off the hydrocarbon vapors, collecting the liquid metal and unvaporized and condensed hydrocarbons in a pool and flashing said unvaporized and condensed hydrocarbons collecting on the surface of the highly heated liquid metal into a separate chamber and withdrawing volatiles, liquids and solids from the system.

15 7. A method of converting hydrocarbons, comprising intermingling the hydrocarbons with liquid mercury heated under pressure to a temperature high enough to bring the mixture of hydrocarbons and mercury to conditions sufficient to convert the hydrocarbons, passing the mixture thru a thermolyzing zone in a stream of restricted cross sectional area, introducing the mixture into a zone of subatmospheric pressure, distilling off the hydrocarbon vapors and collecting the mercury in a pool, withdrawing volatile, liquid and solid material.

20 8. A method of thermolyzing hydrocarbons, comprising heating under pressure, a continuously advancing stream of liquid metal to a temperature above the cracking temperature of hydrocarbons heated to a lesser degree introducing these two streams of heated metal and hydrocarbons substantially in the liquid phase into a thermolyzing zone of restricted cross sectional area, advancing this stream of oil and metal in a rotating motion thru the thermolyzing zone and introducing same into an expansion chamber under pressure reduction, distilling off and removing the vapors and collecting the liquid metal and residual and condensed hydrocarbons in a pool in the bottom part of the expansion chamber, withdrawing part of the highly heated metal and the residual hydrocarbons from the aforementioned pool and flashing the same into a separate chamber under a pressure sufficiently low to bring about copious evaporation of the hydrocarbons in presence of the highly heated metal and over a pool of highly heated metal and withdrawing volatiles, liquids and solids.

25 9. A method of converting hydrocarbons according to claim 1, further characterized in that

the oil is thermolyzed under reduced pressure by means of heated mercury, at a reduced pressure while passing substantially in liquid phase into the zone of reduced pressure, in distilling off and 5 fractionating the vapors and collecting residual hydrocarbons, liquid mercury and condensed material in a pool, flashing the residual hydrocarbons and condensate and part of the highly heated mercury into a separate chamber under a 10 pressure sufficiently low to bring about copious vaporization of the hydrocarbons, introducing steam into the pool in the base of the fractionator as well as into the flashing chamber and withdrawing volatiles, liquids and solids from the 15 system.

10. A method of converting hydrocarbons according to claim 5, further characterized in that the vapors removed from the fractionator under pressure are condensed under reduced pressure 20 and part or all of the condensate is returned to the fractionator by forcing it thru the pool of highly heated metallic liquid and residual and condensed hydrocarbons and the residue in the flasher is withdrawn for further treatment.

25. 11. A method of converting hydrocarbons according to claim 3, further characterized in that the volatile hydrocarbons distilled off in the zone of reduced pressure undergo dephlegmation in the upper part of this zone, the uncondensed 30 vapors being removed under reduced pressure and condensed and part of the condensate is returned to the dephlegmating zone while part of the condensate is returned to the zone of reduced pressure by forcing it thru the pool of metallic liquid in the base of the zone of reduced pressure.

35. 12. A method of converting hydrocarbons according to claim 1, further characterized in that part of the hydrocarbons to be treated are introduced into the top of the zone of reduced pressure 40 before coming into contact with the heated mercury, flowing countercurrent to the ascending vapors and contacting with the heated mercury and residual hydrocarbons.

45. 13. A method of thermolyzing hydrocarbons according to claim 4, further characterized in that the uncondensed vapors from the expansion chamber are condensed under reduced pressure but still above atmospheric pressure and part of 50 this condensate is forced back into the fractionator under increased pressure mingling in the top of the fractionator with part of the untreated charging stock to be withdrawn from the fractionator together with reflux-condensate and 55 forced back into the charging stock, in order to be rethermolyzed.

60. 14. A method of thermolyzing hydrocarbons according to claim 4, further characterized in that the heated mercury and the oil each enter the thermolyzing zone under pressure reduction, 65 impinging upon each other at such an angle that the mixture is given a forward rotating motion whereby the mercury and oil are churned and intimately mixed, to avoid skin-cracking and carbon formation, whence the stream of this mixture enters the expansion chamber, under further reduction of pressure, at or near the point where part of the oil from the charging stock enters the expansion chamber under pressure reduction, both streams impinging on a baffle plate in the expansion chamber, whereby the thermolyzed oil is mixed with the cooler oil at the time when expansion occurs.

70. 15. A method of thermolyzing hydrocarbons 75 according to claim 4, further characterized in

that the uncondensed fractionated vapors are withdrawn from the expansion chamber and condensed under reduced pressure, and part of the condensate is forced back into the charging stock for retreatment and another part of the condensate is forced thru the pool in the base of the expansion chamber, while steam is simultaneously forced thru the aforementioned pool.

16. A method of converting hydrocarbons according to claim 1, further characterized in that part of the hydrocarbons to be treated are introduced into the top of the zone of reduced pressure before coming into contact with the heated mercury, flowing countercurrent to the ascending vapors and contacting with the heated mercury 15 and residual hydrocarbons, reflux condensate is withdrawn from the top of the dephlegmator at a point above that where the split feed is introduced, and returned to the charging stock for further treatment.

20. 17. A method of thermolyzing hydrocarbons according to claim 4, further characterized in that the uncondensed fractionated vapors are withdrawn from the expansion chamber and condensed under reduced pressure and part or all of 25 the condensate is forced back into the charging stock for retreatment.

25. 18. A method for converting hydrocarbons according to claim 1, further characterized in that the vapors and gases are removed from the zone 30 of reduced pressure for further treatment; the mercury and unvaporized cracked residue is collected in a pool into which superheated steam is introduced to contact and mix with the highly-heated mercury and cracked residue; the residue 35 and part of the hot mercury are flashed together into a flasher kept under a subatmospheric pressure to insure a substantially complete removal of all volatile matter from the residue collecting over a pool of hot mercury, while superheated 40 steam is simultaneously introduced into the flasher thru the pool of hot mercury, mixing and contacting with the residue and aiding in the removal of gaseous, volatile and suspended or 45 soluble material from the residue; and the gases, vapors and a substantially dry carbon are removed from the system and recovered.

50. 19. A method of converting hydrocarbons according to claim 2, further comprising feeding part of the preheated charging stock into the top 55 of the zone of reduced pressure, whence it flows, countercurrently to and in intimate contact with the ascending vapors, into a pool of residual, feed and condensed hydrocarbons, collecting over a pool of highly-heated mercury, forcing pressure 60 distillate thru the pool of highly-heated mercury and into the overlying pool of liquid hydrocarbons, continuously withdrawing residual hydrocarbons from the surface of the mercury pool for further treatment, continuously removing 65 vapors and gases from the zone of reduced pressure for further treatment.

20. A method of converting hydrocarbons according to claim 5, further characterized in that the vapors removed from the fractionator are 70 condensed under pressure in open communication with the fractionator.

21. A process for cracking oil which comprises 75 intimately mixing oil and heated molten metal in a confined stream, maintaining said mixture in 80 said confined stream to cause cracking of said oil, separating oil vapor from said metal and residual carbonaceous matter from said oil in a separating zone, reheating said separated molten metal, returning said reheated molten metal to 85

5 said confined stream, withdrawing a portion of said molten metal and carbonaceous matter from said separating zone, treating said withdrawn molten metal and said residual carbonaceous matter in a treatment zone and returning said molten metal to said separating zone.

10 22. An apparatus for cracking oil which comprises means for heating oil under pressure, means for expanding said oil, means for intimately mixing said oil with hot molten metal to crack said oil, means for separating said hot molten metal from said cracked oil, means for reheating said separated molten metal, and means for returning said reheated molten metal to said mixing

15 means.

20 23. A process for cracking oil which comprises heating oil under pressure, expanding said heated oil, intimately mixing said oil with hot molten metal to crack said oil, separating said hot molten metal from said cracked oil, reheating said separated molten metal, and returning said reheated molten metal to the cracking zone.

25 24. An apparatus for cracking oil which comprises means for heating oil under pressure, means for releasing the pressure on said heated oil, means for intimately mixing said pressure released oil with hot molten metal to effect cracking of said oil, means for separating said hot molten metal from said cracked oil, means for reheating said separated molten metal, and means for effecting a cyclic circulation of said molten metal through said mixing, separating and re-heating means.

30 35 25. An apparatus for cracking oil which comprises means for heating oil under pressure, means for releasing the pressure on said heated oil, means for mixing said oil with hot molten metal to crack said oil, means for separating said molten metal from said cracked oil, means for reheating said molten metal, and means for effecting a cyclic circulation of said molten metal through said mixing, separating and reheating means.

35 26. An apparatus for cracking oil which comprises means for intimately mixing oil with hot molten metal in a confined stream to crack oil, means for separating said hot molten metal and residual carbonaceous matter from said cracked oil, means for reheating said separated molten metal, means for returning said reheated molten metal to said mixing means, means for withdrawing a portion of said molten metal and residual carbonaceous matter from said separating means, means for treating said withdrawn molten metal and said residual carbonaceous matter, and means for returning said treated molten metal to said separating means.

40 10 15 20 25 26. An apparatus for cracking oil which comprises means for intimately mixing oil with hot molten metal at a temperature sufficient to crack said oil, means for separating said hot molten metal and residual carbonaceous matter from said cracked oil, means for reheating said separated molten metal, means for returning said reheated molten metal to the mixing means, means for withdrawing a portion of said molten metal and residual carbonaceous matter from said separating means, means for treating said withdrawn molten metal and said residual carbonaceous matter, and means for returning said treated molten metal to said separating means.

30 35 40 28. An apparatus for cracking oil which comprises means for heating oil under pressure, means for expanding oil through an expansion valve to a cracking coil, means for introducing hot molten metal into said cracking coil, means for separating said molten metal from said oil, means for withdrawing a portion of said molten metal and carbonaceous matter from said separating means, means for treating said carbonaceous matter and molten metal, means for reheating said treated molten metal, and means for returning said reheated molten metal to said cracking coil.

ALFRED OBERLE.
